UNITED STATES PATENT OFFICE

FRANCIS H. TOMLIN, OF HADDONFIELD, NEW JERSEY.

TOY.

1,040,058.

Specification of Letters Patent.

Patented Oct. 1, 1912.

Application filed January 23, 1912. Serial No. 672,869.

To all whom it may concern:

Be it known that I, FRANCIS H. TOMLIN, a citizen of the United States, residing in Haddonfield, New Jersey, have invented certain Improvements in Toys, of which the following is a specification.

My invention relates to that class of toys which consist of a box or casing containing a central receptacle and a series of balls which by manipulation of the casing are directed into said receptacle, my invention consisting of a toy of this type in which the direction of the balls into the receptacle is rendered more difficult by mounting the latter and the balls upon a tilting platform, and the invention comprising certain constructions and combinations of parts hereinafter specifically set forth and claimed.

In the accompanying drawing—Figure 1 is a plan or top view, on an enlarged scale, of a toy constructed in accordance with my invention; Fig. 2 is a vertical transverse section of the same on the line $a-a$, Fig. 1, and Fig. 3 is a perspective view of the tilting platform and of the receptacle thereon.

In the drawing, 1 and 2 represent the members of the inclosing casing, the member 1 being a cup, preferably in the form of a saucer shaped disk of any suitable material, preferably sheet metal, and the member 2 being a cover of glass, or other transparent material, through which the balls 3 can be viewed so as to cause the proper direction of the same by manipulation of the casing.

The disk 1 has a centrally disposed and upwardly projecting pivot lug 4 preferably formed by striking up the metal of which the disk is composed, as shown in Fig. 2, and upon this lug is pivotally mounted the tilting platform 5, the latter having a semi-spherical boss 6 struck-up therefrom and centrally disposed thereon, which boss is of a diameter greater than that of the top of the lug 4 so as to permit of the free tilting of the platform 5 in any direction without risk of binding upon the lug.

Centrally located upon the top of the platform 5 is a segmental flange 7, the diameter of the segment being considerably in excess of that of the boss 6 and said segment inclosing a space which the balls can enter and leave only at the gap 8 between the ends of the flange. The flange is preferably secured to the tilting platform 5 by means of downwardly projecting spurs 9 which are

passed through openings in the platform and then bent below the latter, as shown in Fig. 2.

The transparent cover 2 of the casing preferably rests upon a shoulder 10 formed by bending outward the metal of which the disk 1 is composed, said metal being then bent so as to form an upwardly projecting flange 11, which is slotted at intervals so as to form clips 12, which are bent down over the cover 2 and serve to firmly confine the same to its seat upon the shoulder 10.

Owing to the saucer shape of the disk 1 the same cooperates with the lower portion of the tilted platform 5 to form a raceway 70 for the balls 3, hence the latter will move quickly from one position to another along said raceway as the casing is manipulated, the platform 5 tilting freely as the balls change their position and thereby increasing 75 the difficulty of directing the balls through the gap 8 and into the space within the segmental flange 7. The central boss 6 aids, in a measure, in retaining the balls in the enclosure within the flange 7 when they have 80 once been directed into the same.

The top of the flange 7 bears such relation to the cover 2 of the casing that while free tilting of the platform 3 is permitted, said platform cannot rise sufficiently from the 85 pivot lug 4 to permit it to slip laterally therefrom, nor is there sufficient space between the top of the flange 7 and the cover 2 to permit the balls to pass between said flange and cover, the only means of entrance 90 for the balls into the inclosure within the flange or exit of the balls from said inclosure being through the gap 8.

I claim:

1. The within described toy consisting of 95 a saucer shaped disk with transparent cover forming a casing, a centrally pivoted and tilting platform therein and a series of balls which are free to travel in a raceway formed in part by the platform and in part by the 100 dished side of the disk, said tilting platform having upon it a central inclosure with entrance thereto at the side.

2. A toy comprising a casing with transparent top, a centrally pivoted and tilting platform, and a series of balls, the tilting platform having a central inclosure with entrance thereto for the passage of the balls and the top of said inclosure bearing such relation to the transparent top of the casing 110

as to prevent the tilting platform from rising from its pivot sufficiently to slip laterally therefrom.

3. A toy comprising a casing with trans-
5 parent top, a centrally pivoted tilting plat-
form in said casing, a series of balls, and a
receptacle therefor on the platform, the cas-
ing having a central hollow lug struck-up
therefrom and the platform having a central
10 raised boss thereon, said lug constituting the
pivot member of the casing and said boss
the pivot member of the platform.

4. A toy comprising a casing consisting of
a saucer shaped disk with transparent top,

and a centrally pivoted tilting platform 15
with central receptacle thereon, and a series
of balls, the disk having a shoulder thereon
upon which the transparent top is seated
and said disk also having fingers bent down
over the top so as to confine the same firmly 20
to the shoulder.

In testimony whereof, I have signed my
name to this specification, in the presence of
two subscribing witnesses.

FRANCIS H. TOMLIN.
